UNITED STATES PATENT OFFICE

171,923

WHEELED TOY HORSE

Harold D. Allen, East Hampton, Conn.

Application April 20, 1953, Serial No. 24,589

Term of patent 7 years

(Cl. D34—15)

To all whom it may concern:

Be it known that I, Harold D. Allen, a citizen of the United States, residing at East Hampton, in the county of Middlesex and State of Connecticut, have invented a new, original, and ornamental Design for a Wheeled Toy Horse, of which the following is a specification, reference being had to the accompanying drawing, forming part thereof.

In the drawing:

Fig. 1 is a top plan view of a wheeled toy horse showing my new design;

Fig. 2 is a side elevational view thereof;
Fig. 3 is a bottom plan view; and
Fig. 4 is a front elevational view.

I claim:

The ornamental design for a wheeled toy horse, substantially as shown.
